UNITED STATES PATENT OFFICE.

KUWAKICHI FUJITA, OF HAZLETON, PENNSYLVANIA.

BURGLAR-ALARM.

1,383,924.

Specification of Letters Patent.

Patented July 5, 1921.

Application filed November 19, 1918. Serial No. 268,191.

To all whom it may concern:

Be it known that I, KUWAKICHI FUJITA, a subject of the Emperor of Japan, residing at Hazleton, in the county of Luzerne and State of Pennsylvania, have invented new and useful Improvements in Burglar Alarms, of which the following is a specification.

This invention relates to burglar alarms and the present invention is an improvement upon that filed jointly by Gertrude N. Markle and me on April 24, 1918, Serial No. 230,539.

The object of the present invention is to provide improved means for actuating the device and for improving certain details of construction.

With the above and other objects in view the improvement resides in the construction, combination and arrangement of parts set forth in the following specification and falling within the scope of the appended claims.

In the drawings:

Figure 1 is a rear view of the invention with the back part of the case removed,

Fig. 2 is a section on the line 2—2 of Fig. 1,

Fig. 3 is a section on the line 3—3 of Fig. 1,

Fig. 4 is a view of the actuating means,

Fig. 5 is a side view, partly in section, of the trigger releasing means,

Fig. 6 is a sectional detail showing the trigger and barrel, and

Fig. 7 is a view of the case which contains the parts.

As before stated the present invention is an improvement over that contained in the application now on file in the Patent Office.

In the said application a device is shown consisting of a central actuating device and a casing located in each room and containing a rotatable block having a number of barrels therein adapted to contain cartridges

and a housing connected with the block and containing triggers, with means actuating from the central actuating device for rotating the block and releasing the trigger. In the drawings 1 indicates the casing, one of

which is located in each room. 2 indicates the block rotatably mounted in the casing and containing a number of barrels 3. 4 is the housing secured to one side of the block and containing the triggers 5. These triggers are actuated by the springs 6 and

each trigger has connected therewith a rod 7 extending transversely across the block and projecting through a slot 8 in the casing. 9 indicates an actuating rod slidably secured to one side of the casing and carrying bent arms 10 for engaging the ends of the rods 7. The upwardly extending ends of these arms are of different lengths, the shortest one being at the top of the rod and the longest one at the bottom so that when the rod 9 is lowered the cartridges will be fired successively beginning at the top. The lower end of the rod 9 is bent at right angles to provide a hook 11. The other side of the casing slidably carries a releasing rod 12, the upper end of which is adapted to engage with a hole 13 in the top of the casing to hold the block against turning movement, which movement is given the block by means of the spring 14 engaging the cable 15 secured to the drum 16. This arrangement is shown in the other application. The lower end of the rod 12 is provided with a hook 17.

The means for actuating the rods 9 and 12 consists of a roller 18 carried by a shaft 19 journaled in the lower part of the case. A toothed disk 20 is secured to said shaft and a spring dog 21 carried by the bottom of the case engages with the teeth as shown. 22 indicates a spool journaled in the case and provided with a key-receiving socket 23, by which the spool may be rotated by a suitable key. 24 indicates a fan shaft journaled in the casing and provided with the blades 26. This shaft carries a pair of spools 27 and 28. 29 indicates a ribbon having one end secured to the spool 28 and its other end connected with the spool 22. This ribbon passes around a part of the roller 18. 30 indicates another ribbon secured to the spool 27 and to a part of the roller 18. These ribbons are wound around the spools 27 and 28 in opposite directions so that when the spool 22 is rotated by a key the ribbon 29 will unwind from the spool 28 so as to rotate the shaft 24 and thus wind the ribbon 30 upon the spool 27 and unwind it from the roller 18 and thus rotate said roller, the dog 21 slipping over the teeth and thus permitting this action.

31 indicates a shaft journaled in the casing and carrying a pair of spools 32 and 33. 34 indicates a ribbon wound upon one part of the spool 32. The other end of said ribbon is wound upon a spool 35 secured to

the shaft 19 and so connected with said spool 35 that when the ribbon 30 is being unwound from the roller 18 said ribbon 34 will be wound upon the spool 35 and will be unwinding from the spool 32. A cable 36 is wound upon the other part of the spool 32 in an opposite direction from the ribbon 34 and this cable is connected to a coiled spring 37 having its upper end connected with the case. The spool 33 has wound thereon a cable 38 which carries a hook 39 at its free end which is adapted to engage a part 40 on a releasing bar 41 which is provided with a hook 42 at its upper end and has its lower end sliding in a guide 43. This guide 43 may contain a spring for normally holding the bar 41 in its raised position.

It will thus be seen that when the spool 22 is wound up by a key the ribbons will act to wind up the cable 36 on the spool 32 and thus store up energy in the spring 37. The spring is held in extended position by the dog 21 engaging the teeth of the disk 20.

When the device is to be actuated a button 45 is pressed at the central station which closes an electric circuit 46 which includes magnets 47. An armature 48 is secured to the dog 21 so that when the magnets are energized the dog will be moved out of contact with the teeth on the disk so as to permit the spring 37 to revolve the spools and rollers and thus wind up the cable 38. This action will lower the bar 41 and as the hook 42 thereof is in engagement with the rod 12 said rod 12 will be disengaged from the opening 13 and the springs 14 will rotate the block a half turn so as to cause the muzzles of the barrels to face the opening 50 in the front of the case and thus aim 40 into the interior of the room. This turning movement of the block will bring the hook 11 of the rod 9 into engagement with the recess formed by the spaced members of the hook 42 on the rod 41. In this manner the continued downward movement of the rod 41 will move the rod 9 downwardly and thus successively release the rods 7 from the arms 10 so that the cartridges will be fired.

From the foregoing description taken in connection with the accompanying drawings the simplicity and advantages of the improvement will, it is thought, be perfectly apparent to those skilled in the art to which such invention appertains without further detailed description.

I desire it to be understood that I may make changes in the construction and in the combination and arrangement of the several parts, provided such changes fall within the scope of the appended claims.

Having thus described the invention, what I claim is:

1. A device of the class described comprising a rotatable member, cartridge-receiving barrels therein, trigger mechanism carried by said member, means for rotating said member to bring the barrels into firing position, a rod for holding said member against rotation, a second rod having arms thereon of different lengths, rods connected with the trigger mechanism and engaged by said arms for holding the triggers cocked, a vertically movable rod having parts thereon for engaging the holding rod when the member is in non-firing position and the arm carrying rod when the member is in firing position and a spring motor for actuating said vertically movable rod.

2. A device of the class described comprising a rotatable member, cartridge-receiving barrels therein, trigger mechanism carried by said member, means for rotating said member to bring the barrels into firing position, a rod for holding said member against rotation, a second rod having arms thereon of different lengths, rods connected with the trigger mechanism and engaged by said arms for holding the trigger cocked, a vertically movable rod having parts thereon for engaging the holding rod when the member is in non-firing position and the arm carrying rod when the member is in firing position, a spring motor for actuating said vertically movable rod and means for causing the motor to actuate from a distant point.

3. A device of the class described comprising a casing, having an opening therein, a block rotatably mounted in the said casing, spring means for holding the block upon the side opposite said opening, cartridge-receiving barrels in said side, a slideable rod on said block for engaging a part of the casing for holding the block with the barrel carrying side away from said opening, trigger mechanism on said block opposite the barrels, a slideable rod on the block for holding the trigger mechanism cocked, a vertically movable rod supported by the casing and having a part adapted to engage one of the rods when the block is in one position and another part adapted to engage the other rod when the block is in another position, a spring motor in the casing for moving said vertically movable rod downwardly and means for causing said motor to actuate from a distant point.

In testimony whereof I have affixed my signature.

KUWAKICHI FUJITA.
